No. 36,517.

Patented August 25, 1903.

UNITED STATES PATENT OFFICE.

JOSEPH E. STRAKER, JR., OF ATTLEBORO, MASSACHUSETTS, ASSIGNOR TO THE WATSON AND NEWELL COMPANY, A CORPORATION OF RHODE ISLAND.

DESIGN FOR A HANDLE FOR SPOONS OR SIMILAR ARTICLES.

SPECIFICATION forming part of Design No. 36,517, dated August 25, 1903.

Application filed July 25, 1903. Serial No. 167,050. Term of patent 7 years.

To all whom it may concern:

Be it known that I, JOSEPH E. STRAKER, Jr., a citizen of the United States, residing in the town of Attleboro, in the county of Bristol 5 and State of Massachusetts, have invented a new, original, and ornamental Design for the Handle of a Spoon or Similar Article, of which the following is a specification, reference being had to the accompanying drawings, forming part thereof.

Figure I represents the obverse face of the design embodied in the handle of a spoon, and Fig. II shows the reverse side of the same.

The design itself is executed in relief. What I claim as new, and desire to secure 15 by Letters Patent, is—

The ornamental design for the handle of a spoon or similar article as shown.

In testimony whereof I have affixed my signature in presence of two witnesses.

JOSEPH E. STRAKER, JR.
